US0D1065668S

(12) **United States Design Patent** (10) **Patent No.:** **US D1,065,668 S**
(45) **Date of Patent:** **** Mar. 4, 2025**

(54) **CONSUMABLE FOR A VAPORIZER DEVICE**

(71) Applicant: **JUUL Labs, Inc.**, San Francisco, CA (US)

(72) Inventors: **Brandon Cheung**, San Francisco, CA (US); **Matthew J. Malone**, Los Angeles, CA (US)

(73) Assignee: **JUUL Labs, Inc.**, Washington, DC (US)

(**) Term: **15 Years**

(21) Appl. No.: **29/851,807**

(22) Filed: **Aug. 31, 2022**

(51) **LOC (15) Cl.** **27-07**

(52) **U.S. Cl.**

USPC **D27/162**

(57) **CLAIM**

The ornamental design for a consumable for a vaporizer device, as shown and described.

DESCRIPTION

FIG. 1 is a top, rear, and right side perspective view of a consumable for a vaporizer device of our design;

FIG. 2 is a top view thereof;

FIG. 3 is a bottom view thereof;

FIG. 4 is a right side view thereof;

FIG. 5 is a left side view thereof;

FIG. 6 is a front view thereof; and,

FIG. 7 is a rear view thereof.

The broken lines in the drawings depict portions of the consumable for a vaporizer device that form no part of the claimed design.

1 Claim, 5 Drawing Sheets
